JOHN KILLGORE, G. D. CLAP SADDLE, AND EDWARD SNART, OF ARCOLA,
ILLINOIS.

Letters Patent No. 65,577, dated June 11, 1867.

POST-HOLE AUGER.

The Schedule referred to in these Letters Patent and making part of the same.

TO ALL WHOM IT MAY CONCERN:

Be it known that we, JOHN KILLGORE, G. D. CLAPSADDLE, and EDWARD SNART, of Arcola, in the county of Douglas, and in the State of Illinois, have invented certain new and useful Improvements in Post-Hole Augers; and do hereby declare that the following is a full, clear, and exact description thereof, reference being had to the accompanying drawings, and to the letters of reference marked thereon.

In the annexed drawings, making part of this specification, A represents a platform upon which are erected two uprights A' A', said uprights being connected together at their upper ends by a cross-tie, P. On the inner sides of the uprights A' A' are formed grooves which run longitudinally of them. B represents a metallic frame, which is provided with lugs on its edges which play in the grooves in the uprights acting as guides for the frame B. C represents a shaft which has upon each end a crank-handle. This shaft lies across the frame B, having suitable bearings in its sides, with proper caps for covering said bearings. D represents a bevel-wheel which is secured upon the shaft C, which gears into a bevel-wheel, I, upon a vertical shaft, H. E represents a clutch-pulley upon shaft C. G represents a band, one end of which is attached to the cross-tie P, and one end to the clutch-pulley E. This band serves to raise and lower the frame B. When the clutch-pulley does not catch into its counterpart on the wheel D it is loose on the shaft C. The vertical shaft H is provided at its lower end with a slot, in which is pivoted the upper end of a sleeve, J. J represents a metallic sleeve, which is provided at its lower end with the auger-wings L L. K represents a pin which is pointed at its lower end, and which extends up through the sleeve J. A pivot-pin, a, passes through the pin K and through a slot, x, in the sleeve, and then through lower end of shaft H, thus pivoting the sleeve and its pin K in the slot of said shaft H. The slot x allows the pin K to play up and down in the sleeve J. There is sufficient space around the pin K, between it and the sleeve, to allow air to pass through said sleeve.

In boring a post-hole with this machine, the sleeve J, with its wings and the point of pin K, forms an auger which is revolved by the bevel-wheels I and D, and is raised and lowered by the frame B. When this auger takes into the earth the pin K is thrust into the earth as deep as the slot in the sleeve will allow it to go, and when it is being drawn out the pin K draws into the sleeve and allows air to pass down through said sleeve into the hole below the auger-wings to prevent suction and render it easy to withdraw the auger. When the auger has been withdrawn from the hole it may be turned up on the pivot a, out of the way, for the purpose of cleansing it.

Having thus fully described our invention, what we claim as new, and desire to secure by Letters Patent, is—
The arrangement of the sleeve J and its pin K with the shaft H, frame B, and band G, substantially as and for the purpose herein specified.

In testimony that we claim the foregoing we have hereunto set our hands and seals this 25th day of February, 1867.

JOHN KILLGORE,
G. D. CLAPSADDLE,
EDWARD SNART.
